PACKAGE, PACKAGE OPENER, AND STAMP
CANCELER

Leroy Valentine Bell, Wakefield, R. I.

Application May 11, 1939, Serial No. 273,116

2 Claims. (Cl. 229—51)

This invention relates to a package and to means for opening the package, such as a package of cigarettes, and at the same time canceling a revenue stamp, the general object of the invention being to provide a package, the wrappings of which will enclose articles, such as cigarettes, and provide supporting means for a stamp and to provide a string so arranged in parts of the wrapping means that when the string is pulled upon it will cut a portion of the wrapper means and form an opening through which the contents of the package can be removed and at the same time the string will destroy or mutilate the revenue stamp.

While the invention is mainly designed for use on cigarette packages as is shown and described in the present application, it will be understood that it can be used on packages containing other commodities.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which—

Figure 1 is a view of the three wrappers of a package in flattened out condition and with the string in position ready for the package to be wrapped and the stamp applied.

Figure 2 is a view looking toward the inner side of the wrapper shown in Figure 1.

Figure 3 is a view of the wrapper positioned around a package of cigarettes and with the top flap ready to be folded.

Figure 4 is an end view of the package completely folded.

Figure 5 is a view similar to Figure 4 but showing the parts after the string has been pulled upon to remove a portion of the top of the package and also to mutilate the revenue stamp.

Figure 6 is a section on the line 6—6 of Figure 4.

Figure 7 is a side view of the complete package and showing an additional stamp thereon.

Figures 8 and 9 are end views showing different arrangements of the cord under the revenue stamp.

In these drawings, the letter A indicates the outer wrapper, the letter B indicates the tin foil wrapper and the letter C indicates the lining or interior wrapper. These wrappers are folded on

the dotted lines 1 to cover the cigarettes 2 but in carrying out the invention I make the outer covering A shorter or less width than the other wrappers so that it does not extend over the stamp receiving end of the package. This wrapper A is provided with a pair of flaps 3, these flaps being spaced apart and have their free ends flush with the adjacent end edges of the wrappers B and C. These flaps 3 are so arranged that when the wrappers are placed around the package the flaps will be opposite each other at the top as shown in Figure 3 and then when they are pressed downwardly they will overlap.

A string or other flexible member of any suitable type as shown at 4 and has a portion fastened by glue or the like to the inner face of the lining C on a portion thereof which forms the top of the wrapping, one end of the string being shown at a and it extends transversely across the top forming part of the wrapper then along the fold line as shown at b and then transversely again parallel to a side of one of the flaps 3 as shown at c. Then the string is passed through the short slit 5 made in the two wrappers B and C and is passed over the flaps 3 and then passed from the flaps to provide a considerable free length of string as shown at d and this end may be provided with the knots e. Where the string passes over the flap 3 it is provided with a plurality of loops such as shown at 6 or it may be formed into the loops shown at 6' in Figure 8 or 6'' in Figure 9 or being so looped as to take any other form.

The parts a, b and c of the cord or string form a rectangle at one end of the upper end of the package as shown more particularly in Figure 4 when the wrappings are folded about the package with the parts d extending from one corner of the overlapping flaps and these flaps are to receive the revenue stamp S which covers the looped portion 6 of the string when in place. In some cases a second revenue stamp S' is required to be placed on the package, such as that used for a State and in this case it may be placed over the extended part d of the string as shown in Figure 7 and it will be seen from this figure that when the string is pulled upon both stamps will be mutilated. Then after the string has mutilated the stamp it will cut a rectangular opening in one end or the upper end of the package as shown in Figure 5 so that the cigarettes or other contents of the package can be removed therefrom. The flaps provide a reinforcement for the end of the package and provide a stiff end wall for the opening and said

flaps also provide a firm foundation for the revenue stamp S and a support for the looped part of the string which is used to mutilate the stamp.

It is thought from the foregoing description that the advantages and novel features of the invention will be readily apparent.

It is to be understood that changes may be made in the construction and in the combination and arrangement of the several parts provided that such changes fall within the scope of the 10 appended claims.

Having described the invention, what is claimed as new is:

1. A cigarette package comprising an inner wrapper enclosing the sides, edges and upper 15 and lower ends of the pack, an outer wrapper having its top open and forming a receptacle for the wrapped pack, a pair of flaps connected with intermediate portions of the upper edges of the sides of the receptacle and said flaps overlapping each other and extending across the top of the pack when folded, a tearing string folded to form a rectangular loop at one end thereof, said loop being connected to the inner face of the top of the inner wrapper, two portions of the 20 loop extending along the side edges of said top portion, another portion extending along an end edge of the top portion and another portion of

the loop extending across that part of the top portion which is alongside one side edge of the folded flaps, a portion of the string passing from the top portion of the inner wrapper, a portion of the 5 string being looped and placed on the outer side of the outermost flap, a sealing stamp covering said flap and the looped portion of the string with the free end of the string extending from the stamp.

2. In a cigarette container embodying a body portion, a pair of side flaps, one folded over the other to close one end of said body portion, a pair of narrow side flaps folded over the first-mentioned flaps and overlapping each other when closed, a sealing strip overlying said narrow flaps and a tearing string having an end portion folded into a rectangular loop on the under face of the first-mentioned flaps with the loop located between the narrow flaps and the top of 25 the side edge of the container, a portion of the string passing over the free edge of one of the first-mentioned flaps, another portion of the string being looped and located on the outer face of the upper narrow flap and under the sealing strip and the remainder of the string extending from between said sealing strip and said narrow flaps and terminating in a free end.

LEROY VALENTINE BELL.
